UNITED STATES PATENT OFFICE.

EDWARD J. KALTENBACH, OF ST. LOUIS, MISSOURI.

DESIGN FOR A BONBON.

SPECIFICATION forming part of Design No. 23,646, dated September 18, 1891.

Application filed May 3, 1894. Serial No. 510,000. Term of patent 7 years.

To all whom it may concern:

Be it known that I, EDWARD J. KALTENBACH, of the city of St. Louis, State of Missouri, have invented a new and original Design for a Bonbon, of which the following is a full, clear, and exact description, reference being had to the accompanying drawing, forming a part hereof.

In the drawing, I have illustrated, in perspective, a bon-bon embodying my design.

The leading feature of my design consists in a main rounded base of the shape of the frustum of a right cone on the smooth upper surface of which rests a smaller ornamental body in relief, having the pattern of a clover-stem and leaves, the marginal edges of which lie within the periphery of the said upper surface.

1 indicates a circular base in the form of a truncated-cone, having a smooth upper surface upon which is mounted a smaller body 2 the marginal edges 3 of which outline a definite figure known as a clover stem and leaves.

What I claim is—
The design for a bon-bon, herein shown and described.

In testimony whereof I affix my signature in presence of two witnesses.

EDWARD J. KALTENBACH.

Witnesses:

M. G. IRION,
JNO. C. HIGDON.
